DINNERWARE DECORATING APPARATUS

Walter H. Emerson, East Liverpool, Ohio, assignor to The Homer Laughlin China Company, Newell, W. Va., a corporation of Delaware

Application February 27, 1943, Serial No. 477,411

23 Claims. (Cl. 91—12)

1

This invention relates to dinnerware decorating machines, and more particularly to machines for applying bands of coating material to articles of dinnerware. The coating may be a glaze or color or the like, but in this specification it shall be referred to as color.

Machines have been proposed heretofore for painting bands on dinnerware, such as on the shoulders of plates and around the outside of cups, but most of them apply the color by means of applicators that engage the ware. For various reasons those applicators have not been satisfactory. In the single case of which I am aware wherein the color was sprayed on the plate around a circular mask temporarily resting on the center of the plate, the machine required too many manual operations to have a satisfactory rate of output, and the inner edges of the colored bands were irregular and smeared. This was due to the use of improperly cleaned masks and to the lack of a tight fit between the ware and the edges of the mask. The machine also lacked satisfactory means for properly centering the ware relative to the mask.

It is among the objects of this invention to provide a banding machine which is automatic, which automatically centers the ware, which sprays on bands of coating, which effectively masks surfaces that are not to receive the coating, which thoroughly cleans the masks after each use, and which is rapid in operation, simple in construction, and easy to operate.

In accordance with this invention a mask is held against a piece of ware while color is applied to the unprotected portion, preferably by spraying. After the ware has been banded it is separated from the mask and the latter is washed and dried before being applied to an unbanded piece of ware. In the case of flat ware, such as plates and saucers, the mask is held against the center of the ware by a vacuum while the surrounding surface of the ware is sprayed with color. At least the edge of the mask is flexible so that it can conform to the adjoining surface of the ware and thus provide a seal. Most suitably, the mask is disposed above the ware so that in order for the vacuum to support the ware the mask must tightly engage the ware, thereby preventing color from spraying or running under the edge of the mask. When the vacuum is released, the ware can be deposited on a conveyor or in the hand of an operator. The mask and ware are preferably rotated while the banding color is being applied, and the mask is rotated during washing and drying. To apply the ware to the mask centrally thereof, the ware is first placed on a centering device directly

2

below the mask and is then raised up to the mask. In the most practical embodiment of my invention a plurality of mask-supporting vertical spindles, preferably rotatable, are carried by an intermittently rotating table by which they are indexed from station to station so that while centering and loading are taking place at one station, banding may occur at another, unloading at another, mask cleaning at another, and mask drying at another. If desired, the masks may serve simply as supports for the ware while other processes, such as lining the edge of the ware, are performed at stations that otherwise would be idle. In the case of lining, an applicator such as shown in my copending application Serial No. 481,737 for Dinnerware decorating apparatus, filed April 3, 1943, now Patent No. 2,380,509, is issued July 31, 1945, may be mounted beside the table for periodically engaging rotating ware adjacent the applicator.

The preferred embodiment of the invention is illustrated in the accompanying drawings in which Fig. 1 is a plan view taken on the line I—I of Fig. 2; Fig. 2 is a vertical section looking in the direction of line II—II of Fig. 1; Fig. 3 is a vertical section looking in the direction of line III—III of Fig. 1; Fig. 4 is a horizontal section taken on the line IV—IV of Fig. 2; Fig. 5 is an enlarged view of a portion of Fig. 2 showing the ware just being applied to a mask; Fig. 6 is a fragmentary plan view of part of the actuating means for the centering device; Fig. 7 is an enlarged vertical section through a head and mask supporting a piece of flat ware; Fig. 8 is a similar view of a modified head supporting a cup; and Fig. 9 is an enlarged fragmentary vertical section through one of the rotary spindles.

Referring to the drawings, a cylindrical housing 1 is provided in the center of its lower portion with a bearing 2 in which the lower end of a vertical hollow shaft 3 is journaled. The shaft extends above the top of the housing and through a bearing 4 mounted on a cylindrical casting 5 supported by the housing. The shaft is turned intermittently by means of a Geneva gear mechanism the spider 7 of which is secured to the lower end of the shaft below bearing 2. The rotor 8 is secured to the lower end of another vertical shaft 9 journaled in upper and lower bearings 10 and 11 mounted in the housing at one side of the center shaft. The central portion of the side shaft carries a sprocket 12 that is driven by a chain 13 from a small sprocket 14 driven by a worm and gear unit 15. This unit is operated by a chain and sprocket drive 16 from a speed reducing unit 17 attached to an electric motor 18.

all within the base of the housing. The drive is shown best in Fig. 4.

Rigidly mounted on the upper end of the center shaft is a circular table 20 carrying at circumferentially spaced intervals around its edge a plurality of downwardly projecting rotatable spindles 21. Each spindle is hollow and supports at its lower end a head 22 to the bottom of which a diaphragm-like mask 23 is secured for the purpose of preventing paint that is sprayed on the ware 24 from reaching the central portion of the ware covered by the mask. The masks are made from a slightly flexible material, such as heavy Celluloid or the like, and preferably are concave so that only their edges engage the ware.

As will be seen in Figs. 2 and 9, each spindle includes a vertical post 25 rigidly connected at its upper end to the table. This post has a flange 26 at its lower end that supports a pair of vertically spaced bearings 27. Encircling and supported by the bearings is a metal cup 28 provided at its upper end with a rotary sealing member 29 that frictionally engages a collar 30 tightly mounted on the post. Integral with the bottom of the cup and projecting downwardly therefrom is a hollow shaft 31 on the lower end of which head 22 is mounted. Rigidly mounted on the cup is an encircling wheel 32 for a purpose to be described later. The post is provided with an axial passage 33 that extends up into collar 30 to meet a radial passage 34 therein. As shown in Fig. 7, the head and mask have central openings aligned with the axial passage in shaft 31 that supports them.

It will be noted that the masks are located several inches above the top of housing 1. Therefore, to hold ware against the bottoms of the masks the air pressure between each mask and adjoining piece of ware is reduced by connecting the supporting spindle to a vacuum pump. Thus, the outer end of passage 34 in collar 30 is connected by a laterally extending pipe 36 to a radial passage in a block 37 mounted on the center shaft. The inner ends of the radial passages in the block communicate with the axial passage of the center shaft. Near its lower end shaft 3 is provided with a radial passage 38 (Fig. 2) that opens into a chamber in a stationary sealing member 39 which is connected by a pipe 40 to a vacuum pump (not shown). Each upper pipe 36 contains a valve, such as the type known as Quik-as-Wink, that has lateral openings 42, shown at the right hand side of Figs. 1 and 2, connecting the inside of the pipe on the spindle side of the valve with the atmosphere and which are periodically opened and closed by the slidable closure member 43. When openings 42 are covered by the closure member, the spindle is connected with the vacuum pump, but when the openings are uncovered to release the vacuum in the spindle, pipe 36 on the other side of the valve is closed off so that the vacuum therein will not be lost.

The valve closure members are moved back and forth by bifurcated valve-actuating arms 44 mounted at one end on the upper ends of vertical shafts 45 that are oscillatable in bearings 46 supported by a stationary ring 47 encircling the upper end of casting 5. The shafts extend down through the top of the housing and, as shown in Fig. 4, are operatively connected to each other by levers 48, 49, and 50 and links 51 and 52. Lever 50 carries a roller 53 at its free end that follows a groove 54 in a cam 55 mounted on the constantly rotating side shaft 9. The cam groove is 75

shaped to swing lever 50 to close each successive vacuum control valve after it reaches the loading station and to open it when it reaches the unloading station.

In order to apply ware to each successive mask at the loading station, as shown in Fig. 5, a lifting plate 57 directly below the mask is mounted on the upper end of a post 58 that is slidably mounted in a tube 59 vertically reciprocable in a tubular bearing 60 extending downwardly from the top of the housing. Projecting from the bottom of the tube is a bearing member 61 which supports a roller 62 that is prevented from turning on a vertical axis by means of a lug 63 that projects from the tube into a vertical guideway 64 in a bar-like extension of the tubular bearing. The roller is supported by a cam 65 that is rigidly mounted on the continuously rotating side shaft 9 and that periodically raises the roller and thus lifts plate 57 toward a mask 23 above it. The roller is held down on the cam at all times by a coil spring 66 connected to the tube and the main housing below it. The vertical movement of post 58 in tube 59 is limited by a pin 67 projecting from the post into a vertical slot 68 in the tube. The post is normally maintained in its upper position in the tube by a coil spring 69 compressed between the bottom of the post and the top of bearing member 61. This spring permits the post to "give" a little in case some ware is thicker than others, and thereby prevents the ware from being smashed.

For centering the ware on the lifting plate before it is raised, three vertical pins 70 are disposed at equally spaced intervals around the plate. The pins are mounted on the outer ends of arms 71 projecting laterally from short vertical shafts 72 that are oscillatably mounted in a bearing ring 73 fastened to the top of the housing around the tubular bearing 60. The lower ends of these shafts carry pinions 74 that mesh with a gear 75 journaled on the tubular bearing. When this gear is rotated a short distance it turns the pinions and thereby, through arms 71, swings the vertical pins 70 either inwardly or outwardly relative to the center of the lifting plate. When they are swung inwardly, one or two of them engage the ware resting on the plate and shift it laterally until it strikes the remaining pin or pins and is centered relative to the mask above it.

As shown in Fig. 6, to oscillate gear 75 for this purpose, a rod 77 is pivotally connected to it at one end with the other end of the rod extending away from it at a tangent and through one end of a crank 78 that is oscillatably mounted on a pin 79 depending from the top of the housing. The other arm of the crank carries a tapered member 81 that is periodically engaged by a roller 82 affixed to a disc 83 rigidly mounted on the side shaft. When this roller strikes the tapered member it swings the crank and thereby pulls rod 77 to turn the gear. In case the gear does not turn as far as usual, due to the centering pins engaging a piece of ware that is slightly oversize, the ware will not be broken by the pins because the crank will slide on the rod against the compression of a coil spring 84 also mounted thereon. As soon as roller 82 leaves the crank the gear is returned to its original position, in which the pins are spread apart, by a spring 85 connected to the bottom of the housing cover and to the outer end of a third arm 86 that projects from the crank. The centering of the ware occurs while the lifting plate is in its lower posi-

tion, and the centering pins swing away from the ware just before it is raised.

After a piece of ware has been applied to the mask and the lifting plate lowered to its normal position, the table is turned by the Geneva mechanism just far enough to carry the ware to the next station. With the eight-head machine shown in the drawings, the first station to which ware is indexed may be an idle station, in which case the next station should be the one at which the ware is banded with a ceramic color, colored glaze, or other coating, sprayed on the upper surface of the annular portion or shoulder of the ware projecting from the mask. As shown in Fig. 3, this is done by means of a spray nozzle 88 adjustably mounted on a vertically adjustable rod 89 supported at its lower end by a bracket 90 attached to the side of the housing. A spray booth is formed around the ware by a casing 91 mounted on top of the housing. Excess spray is drawn down through an exhaust duct 92 extending from the open bottom of the casing down through the housing.

Rotation of the ware while it is being sprayed may be effected conveniently by a friction wheel 94 adjustably mounted in a block 95 secured to ring 47 that is mounted on center casting 5, as shown in Figs. 1 and 3. This wheel, which frictionally engages wheel 32 on the spindle at the banding station, is rotated by a pulley 96 that is driven by a belt 97 from another pulley 98 mounted on the upper end of a vertical shaft 99. This shaft is journaled in a bearing 100 in ring 47 and extends down through another bearing 101 in the top of the housing. The lower end of the shaft inside the housing carries a pulley 102 (Figs. 3 and 4) that is driven by a belt 103 from a pulley 104 keyed on side shaft 9. As a spindle moves into the spray booth its wheel 32 frictionally engages the constantly rotating wheel 94, whereby the mask and ware are rotated while being sprayed.

The spray is operated only while ware is in the spray booth and rotating. The spray is turned off and on by a valve 106, shown in Fig. 1, mounted on top of the housing. This valve, which is in the air line 107 of the spray, preferably is the type disclosed in my Patent No. 2,241,772 to which reference is made for a detailed description of it. As shown in Fig. 4, the valve is operated by a shaft 108 extending down into the housing and carrying at its lower end a sprocket 109 driven by a chain 110 from a sprocket 111 near the lower end of the side shaft. The chain engages an idler sprocket 112 on center shaft 3. The times at which the spray is turned on and off are selected by adjusting handles 113 projecting from the control valve.

After bending, the ware is indexed to a station that may be idle, or one at which something, such as lining, is performed. An extra driving pulley 114 for rotating the ware at such a station is shown in the drawings. From there the ware is indexed to the unloading station, but before arriving there the friction wheel on the spindle engages a stationary brake block 115, shown in Fig. 1, supported by spring members 116 attached to ring 47. The brake stops rotation of the spindle. When the ware reaches the unloading station the vacuum valve connected to that spindle is automatically opened and the ware drops into the hand of a workman who may inspect it and place it on a conveyor, or it may be deposited directly onto a conveyor belt 117 that carries it away from the machine. If desired, other opera-

tions can be performed on the ware as it is carried along by the belt.

The next time the table turns it carries the mask, that has just released a piece of ware at the unloading station, into the end of an arcuate tunnel-like casing 120 that forms a cleaning chamber. This casing has small openings at its opposite ends and a narrow opening along its top for passage of the spindle into, through, and out of the cleaning chamber. When table 20 comes to rest with a mask at the first station in the cleaning chamber, the mask is sprayed with water from a tube 121. At that time the mask is rotated by a friction wheel 122 (Fig. 1) engaging wheel 32 of the supporting spindle. Wheel 122 is journaled in a bearing 123 mounted on ring 47. At the next station in the cleaning chamber the mask may be sprayed again or it may merely rotate to throw off the water. Rotation is effected by a friction wheel 124 journaled in a bearing 125. At the following station, which is just before the mask leaves the cleaning chamber, water is blown off the mask by an air jet 126 while the mask is rotated by a friction wheel 127 journaled in a bearing 128. This wheel is mounted on the upper end of a shaft 129 that extends down through the top of the housing where it carries a pulley 131 that is driven by a belt 132 from a pulley 133 on shaft 9. Directly below wheel 127 is a pulley 134 connected by a belt 135 to one of a pair of pulleys 136 attached to wheel 124. The other pulley of the pair is connected by a belt 137 to a pulley 138 carried by wheel 122. Thus, all three friction wheels above the cleaning chamber are driven from shaft 29. As the cleaned and dried mask leaves the chamber the spindle wheel 32 engages a brake block 139 supported by spring members 140 from ring 47. The brake stops the spinning of the mask so that it is stationary when it arrives back at the loading station ready to receive a new piece of ware from the lifting plate.

In using this machine an operator at the loading station places a piece of dinnerware upon lifting plate 51 while the latter is in its lower position, as indicated in Fig. 2. While this is happening, the Geneva mechanism is turning table 20 to move a clean mask from cleaning chamber 120 into position above the lifting plate. By the time the table comes to rest the roller 82, carried by disc 83, strikes the projection 81 on crank 78 of the centering device and thereby swings the crank on its pivot as shown in Fig. 6. This causes the crank to pull rod 77 and thereby turn gear 75 a short distance. The gear turns the three pinions 74 and thereby swing centering pins 70 inwardly to engage the plate, as shown in Fig. 1, and center it on the lifting plate. Roller 82 immediately leaves projection 81, so the crank, pulled by spring 85, turns the gear back to its original position in order to swing the centering pins away from the ware. By this time the high part of cam 65 has reached roller 62 by which the lifting plate is elevated to raise the ware up against the mask 23 above it, as shown in Fig. 5.

Just as the ware reaches the mask the lever 50 is swung outwardly by cam groove 54 so that the adjacent vertical shaft 45 is turned in order to swing the adjoining arm 44 at its upper end to the left as viewed in Fig. 1. The arm at this time has become engaged by the closure member 43 of the vacuum valve above it, and this member is therefore pushed to the left to close openings 42 of the valve and to connect the spindle

side of pipe 36 with the other side of the valve which is in communication with the vacuum pump. This connects the vacuum pump with the space between the mask and ware and immediately reduces the air pressure in that space so that the ware is held tightly against the mask (Fig. 7) where it remains when the lifting plate is lowered. The slight flexibility of the mask permits its edge to conform to the upper surface of the ware and form a seal. As the seal must be substantially perfect in order for the ware to be supported by the mask, the edge of the mask must tightly engage the ware whereby any of the coating material that is sprayed on later will be prevented from getting under the mask.

As soon as the lifting plate is lowered, the table is indexed to carry the ware to the next station and to bring a new mask over the lifting plate so that a new piece of ware may be applied to it in the manner just described.

The next time the table is indexed the first piece of ware is moved into the spray booth 91 where it is rotated through the frictional engagement of spindle wheel 32 with the constantly rotating friction wheel 94, as shown in Figs. 1 and 3. As soon as the table comes to rest with the ware rotating in the spray booth, the air control valve 106 (Fig. 1) opens the air line to spray gun 88 and thus starts the spraying of coating upon the upper surface of the ware projecting beyond the mask. Of course, the mask effectively prevents the coating from reaching the masked central portion of the ware. Before the table starts to move again, valve 106 shuts off the air supply to the spray gun and thus stops the spraying so that there is no waste.

The table then moves the banded ware to the next station and carries an unbanded piece of ware from the second station into the spray booth. The banded ware still will be rotating, due to momentum, but when the table is next indexed the spindle wheel 32 above the rotating banded ware will engage brake block 115 (Fig. 1) and stop rotating before it reaches the unloading station. At the same time that the vacuum valve connected to a spindle at the loading station is closed, the vacuum valve connected to the spindle at the unloading station is opened in the same manner to connect the spindle side of the adjoining pipe 36 with the atmosphere. This allows air to enter the spindle and return the pressure between the mask and banded ware to normal so that the banded ware drops away from the mask. It may be caught in the hand of an operator or it may be deposited on a traveling belt 117 by which it is carried away from the machine.

When the table is turned again it carries the mask, that has just released a piece of ware, into the cleaning chamber 120. At the first station inside the chamber the mask and its supporting spindle are rotated by friction wheel 122 (Fig. 1) while a jet of water from tube 121 washes from the mask the coating material that was sprayed upon it in the spray booth. The table is then indexed to carry the mask to the middle station in the cleaning chamber where the mask is rapidly rotated by friction wheel 124 (Figs. 1 and 3). Centrifugal force throws most of the water off the mask, but at the last station in the cleaning chamber, where the mask is rotated by friction wheel 127, the removal of the water is aided by a jet of air from tube 126. By the time the mask leaves the chamber it is clean and dry. As it leaves the chamber the spindle wheel 32 engages brake block 139 by which its rotation is stopped

before the mask reaches the loading station in readiness for a repetition of the cycle just described.

For an article, such as a cup, that is to have a band applied to its outer or lower surface, the type of mask shown in Fig. 8 is used. In this embodiment the bottom of the head 150 mounted on the lower end of the rotatable hollow spindle shaft 151 is provided with an annular recess close to the shaft. Mounted in this recess is a resilient annular sealing member 152 that is engaged by the foot of a cup 153 so that a small space is formed between them from which air is evacuated in order to hold the cup against the head. The mask that shields the part of the cup that is not to be coated is formed from a ring 154 of resilient material, such as rubber, which is attached to the bottom of the head outside of the sealing ring. This mask has a thin lip that engages the cup and conforms to its surface even though in some cases the ring must fit over the lower portion of the cup handle. Heads and masks of this character for use with cups, bowls, and the like are carried by an index table the same as described herein. In the spray booth a coating is sprayed on the outer surface of such ware below the mask.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A dinnerware decorating machine comprising a mask of impervious material adapted to be disposed above the center of a piece of ware, the edge of the mask being capable of forming an air seal with the surface of the ware, means for reducing the air pressure above the ware to hold the ware against said mask, and means for spraying a coating on the masked side of the ware projecting from said mask, said mask shielding the masked area of the ware from said coating.

2. A dinnerware banding machine comprising a mask of impervious material for a piece of ware, the edge of the mask being capable of forming an air seal with the surface of the ware, means for reducing the air pressure above the ware to hold the ware against the mask, means for rotating the mask, means for spraying a coating on the masked side of the ware projecting from the mask, said mask shielding the masked area of the ware from said coating, means for stopping rotation of the mask, and means for restoring said air pressure to release the ware from the stationary mask.

3. A dinnerware banding machine comprising a mask of impervious material for the center of a piece of ware, the edge of the mask being capable of forming an air seal with the surface of the ware, means for reducing the air pressure between the mask and ware to hold the mask against the ware, means for spraying a coating on the ware around the mask, means for restoring said air pressure to release the mask from the ware, means for cleaning the mask to remove the coating sprayed on its edge, and intermittently moving means for carrying the mask from said spraying means to said cleaning means and back again.

4. A dinnerware banding machine comprising a hollow vertical spindle, a concave mask of impervious material secured to the lower end of the spindle and having a central opening communi-

cating with the inside of the spindle, the edge of the mask being capable of forming an air seal with the surface of a piece of ware, suction means connected to the upper end of the spindle for holding a piece of ware against the edge of the mask, means for rotating the spindle, and means for spraying a coating on top of the projecting portion of ware carried by the rotating mask while the central area of the ware is shielded from said coating by the mask.

5. A dinnerware banding machine comprising a hollow vertical spindle, a concave mask of impervious material secured to the lower end of the spindle and having a central opening communicating with the inside of the spindle, the edge of the mask being capable of forming an air seal with the surface of a piece of ware, suction means connected to the upper end of the spindle for holding the top of a piece of ware against the edge of the mask, means for rotating the spindle, means for spraying a coating on top of the projecting portion of ware carried by the rotating mask, means for stopping rotation of the spindle, means for admitting atmospheric pressure to the spindle to cause the sprayed ware to drop from the mask, means for again rotating the spindle, means for cleaning the rotating mask to remove the coating sprayed on its edge, and means for stopping rotation of the spindle before said suction is applied again.

6. A dinnerware banding machine comprising a mask of impervious material and having a central opening and adapted to cover the center of a piece of ware, the edge of the mask being capable of forming an air seal with the surface of the ware, suction means communicating with said central opening, a ware support below the mask, means for moving a piece of ware laterally on said support to center it relative to the mask above, means for raising the support to place the ware against the mask where it is held by suction, means for moving the mask laterally away from said support, and means for applying a coating to the portion of the ware projecting from said mask.

7. A dinnerware banding machine comprising a mask of impervious material and having a central opening and adapted to cover the center of a piece of ware, the edge of the mask being capable of forming an air seal with the surface of the ware, suction means communicating with said central opening, a ware support below the mask, laterally movable vertical centering pins beside said support, means for periodically moving said pins inwardly toward the support to engage a piece of ware and center it thereon relative to the mask above, means for raising the support to place the ware against the mask where it is held by suction, means for moving the mask laterally away from said support, and means for applying a coating to the portion of the ware projecting from said mask.

8. A dinnerware banding machine comprising a hollow spindle, a concave mask of impervious material secured to one end of the spindle and having a central opening communicating with the inside of the spindle, the edge of the mask being capable of forming an air seal with the surface of a piece of ware, suction means connected to the other end of the spindle for holding a piece of ware against the edge of the mask, a wheel rigidly mounted on the spindle, constantly moving friction means, means for periodically bringing said wheel and friction means into frictional engagement with each other whereby to rotate

the spindle, and means for spraying a coating around the rotating mask on ware carried thereby.

9. A dinnerware banding machine comprising a hollow spindle, a concave mask of impervious material secured to one end of the spindle and having a central opening communicating with the inside of the spindle, the edge of the mask being capable of forming an air seal with the surface of a piece of ware, suction means connected to the other end of the spindle for holding a piece of ware against the edge of the mask, a friction wheel rigidly mounted on the spindle, a constantly rotating friction wheel, means for periodically bringing said wheels into frictional engagement with each other whereby to rotate the spindle, means for spraying a coating around the rotating mask on ware carried thereby, and a stationary friction member adapted to be engaged periodically by said spindle friction wheel to stop the rotation of the spindle.

10. A dinnerware banding machine comprising a mask of impervious material for the center of a piece of ware, the edge of the mask being capable of forming an air seal with the surface of the ware, means for reducing the air pressure between the mask and ware to hold the mask against the ware, means for spraying a coating on the ware around the mask, means for restoring said air pressure to release the mask from the ware, means for washing the mask to remove the coating sprayed on its edge, means for rotating the wet mask, means for blowing a fluid on the rotating mask, means for stopping rotating of the mask before another piece of ware is applied to it, and mechanism for indexing the mask from one of said means to the next in succession.

11. A dinnerware banding machine comprising a mask of impervious material and having a central opening and adapted to cover the center of a piece of ware, the edge of the mask being capable of forming an air seal with the ware, suction means communicating with said central opening, a ware support below the mask, laterally movable vertical centering pins beside said support, means for periodically moving said pins inwardly toward the support to engage a piece of ware and center it thereon relative to the mask above, a cam for raising the support to place the ware against the mask where it is held by suction, means for continuously rotating said cam, means operated from said cam-rotating means for actuating said pin-moving means, means for moving the mask laterally away from said support, and means for applying a coating to the portion of the ware projecting from said mask.

12. A dinnerware banding machine comprising a mask of impervious material and having a central opening and adapted to cover the center of a piece of ware, the edge of the mask being capable of forming an air seal with the ware, suction means communicating with said central opening, a ware support below the mask, means for moving a piece of ware laterally on said support to center it relative to the mask above, continuously rotating means for periodically raising said support to place the ware against the mask where it is held by suction, means for moving the mask laterally away from said support, means operated from said continuously rotating means for periodically rotating the mask, and means for spraying a coating on the portion of the ware projecting from said rotating mask.

13. A dinnerware banding machine comprising a mask of impervious material and having a central opening and adapted to cover the center of a piece of ware, the edge of the mask being capa-

11

ble of forming an air seal with the ware, suction means communicating with said central opening, a ware support below the mask, means for moving a piece of ware laterally on said support to center it relative to the mask above, continuously rotating means for periodically raising said support to place the ware against the mask where it is held by suction, means for moving the mask laterally away from said support, means operated from said continuously rotating means for controlling said suction means, and means for applying a coating to the portion of the ware projecting from said mask.

14. A dinnerware banding machine comprising a horizontal table, a plurality of hollow spindles depending from the table at circumferentially spaced points, a mask of impervious material secured to the lower end of each spindle and having a central opening communicating with the inside of the spindle, means for periodically rotating the table to index the masks from station to station, means at a loading station for applying a piece of ware to the mask above it, the edge of the mask being capable of forming an air seal with the surface of the ware, suction means connected to the upper ends of the spindles to hold ware against the masks, means for rotating the ware, means at another station for spraying a coating on top of the projecting portion of the ware carried by the rotating masks, and means for admitting atmospheric pressure to the spindles at a later station to release the ware.

15. A cup banding machine comprising a hollow vertical spindle, a head mounted on the lower end of the spindle and having a central opening communicating with the inside of the spindle, a resilient ring carried by said head and encircling said opening, suction means connected to the upper end of the spindle for holding the foot of a cup against said ring, a resilient ring of larger diameter than said first-mentioned ring but concentric therewith and carried by said head for engaging the side of the cup to form a mask, means for rotating the spindle, and means for spraying a coating on the cup below said mask.

16. A dinnerware banding machine comprising a support, a post projecting downwardly therefrom, a cup-like member rotatably mounted on the lower portion of the post, means sealing the space between the top of said member and the post, a hollow shaft projecting downwardly from the bottom of said member to which it is rigidly connected, a mask of impervious material secured to the lower end of the shaft and having a central opening communicating with the inside of the shaft, the edge of the mask being capable of forming an air seal with the surface of a piece of ware, said post having an axial passage extending from its lower end up to a radial opening in the post above said cup-like member, suction means connected to said radial opening for holding a piece of ware against the edge of the mask, means for rotating said cup-like member, and means for applying a coating around the rotating mask on ware carried thereby.

17. A dinnerware decorating machine comprising a mask for shielding the center of a piece of ware, automatic means for centering ware relative to the mask, means for moving the centered ware against the mask, means for spraying the masked side of the ware around the mask, and means for releasing sprayed ware from the mask.

18. A dinnerware decorating machine comprising a mask for shielding the center of a piece of ware temporarily supported thereby, means for centering ware relative to the mask, means for

12

rotating the mask, means for spraying the masked side of the ware around the rotating mask, and means for automatically releasing the decorated ware from the mask.

5 19. A dinnerware banding machine comprising a horizontal table, a plurality of hollow spindles depending from the table at circumferentially spaced points, a mask of impervious material secured to the lower end of each spindle and having a central opening communicating with the inside of the spindle, means for intermittently rotating the table to index the masks from station to station, means at a loading station for centering a piece of ware relative to the mask above it, means at said loading station for raising the ware into engagement with the mask, the edge of the mask being capable of forming an air seal with the surface of the ware, suction means connected to the upper ends of the spindles to hold ware against the masks, means at another station for spraying a coating band on top of the projecting portion of the ware carried by the rotating masks, means at said spraying station for rotating the spindles, and means for admitting atmospheric pressure to the spindles at a later station to release the banded ware.

15 20. A dinnerware banding machine comprising a horizontal table, a plurality of hollow spindles depending from the table at circumferentially spaced points, a mask of impervious material secured to the lower end of each spindle and having a central opening communicating with the inside of the spindle, means for intermittently rotating the table to index the masks from station to station, means at a loading station for centering a piece of ware relative to the mask above it, means at said loading station for raising the centered ware into engagement with the mask, the edge of the mask being capable of forming an air seal with the surface of the ware, suction means connected to the upper ends of the spindles to hold ware against the masks, means at another station for spraying a coating band on top of the projecting portion of the ware carried by the rotating masks, means at said spraying station for rotating the spindles, and means for admitting atmospheric pressure to the spindles at a later station to release the banded ware.

30 21. A dinnerware banding machine comprising a horizontal table, a plurality of hollow spindles depending from the table at circumferentially spaced points, a mask of impervious material secured to the lower end of each spindle and having a central opening communicating with the inside of the spindle, means for intermittently rotating the table to index the masks from station to station, means at a loading station for centering a piece of ware relative to the mask above it, means at said loading station for raising the centered ware into engagement with the mask, the edge of the mask being capable of forming an air seal with the surface of the ware, suction means connected to the upper ends of the spindles to hold ware against the masks, means at another station for spraying a coating band on top of the projecting portion of the ware carried by the rotating masks, means at said spraying station for rotating the spindles, means for admitting atmospheric pressure to the spindles at a later station to release the banded ware, and mask-cleaning means located at a station beyond said releasing station, whereby each mask is cleaned before the table returns it to said loading station.

45 22. A dinnerware banding machine comprising a horizontal table, a plurality of hollow spindles depending from the table at circumferentially spaced points, a mask of impervious material secured to the lower end of each spindle and having a central opening communicating with the inside of the spindle, means for intermittently rotating the table to index the masks from station to station, means at a loading station for centering a piece of ware relative to the mask above it, means at said loading station for raising the ware into engagement with the mask, the edge of the mask being capable of forming an air seal with the surface of the ware, suction means connected to the upper ends of the spindles to hold ware against the masks, means at another station for spraying a coating band on top of the projecting portion of the ware carried by the rotating masks, means at said spraying station for rotating the spindles, means for admitting atmospheric pressure to the spindles at a later station to release the banded ware, a casing mounted between said releasing station

and said loading station and having an arcuate slot in its top extending lengthwise thereof for receiving said spindles, and means in said casing for cleaning the masks carried therethrough by the spindles.

22. A dinnerware decorating machine comprising an intermittently moving support, a mask carried thereby for shielding the center of a piece of ware held against it, means for spraying a coating on the masked side of the ware around the mask, automatic means for releasing ware from the mask, and automatic means for cleaning the mask before it is returned by said support to said spraying means.

23. A dinnerware decorating machine comprising a plurality of spindles each provided with a central opening, a mask of impervious material at one end of each opening, the edge of the mask being capable of forming an air seal with the surface of a piece of ware, means for applying suction at the other end of each opening to hold ware against the masks, decorating means, means for intermittently moving the spindles and masks past the decorating means, automatic means for releasing decorated ware from the masks, a cas- 25

ing through which the masks are moved by said intermittently moving means after they have released said ware, and means in said casing for cleaning the masks.

WALTER H. EMERSON.
